(57) CLAIM

The ornamental design for a food pick, as shown and described.

DESCRIPTION

FIG. 1 is a perspective view of a food pick; FIG. 2 is a front side view of the food pick; FIG. 3 is a rear side view of the food pick; FIG. 4 is a left side view of the food pick; FIG. 5 is a right side view of the food pick; FIG. 6 is a top view of the food pick; and, FIG. 7 is a bottom view of the food pick. The broken lines shown in the figures illustrate portions of the food pick that form no part of the claimed design.
